Geo. P. Kimmel. BY

ATTORNEY.

UNITED STATES PATENT OFFICE.

ARTHUR T. VINSON, OF JACKSONVILLE, FLORIDA.

SHIPPING RECEPTACLE.

Application filed May 27, 1922. Serial No. 564,129.

To all whom it may concern:

Be it known that I, ARTHUR T. VINSON, a citizen of the United States, residing at Jacksonville, in the county of Duval and

5 State of Florida, have invented certain new and useful Improvements in Shipping Receptacles, of which the following is a specification.

This invention has reference to improvements in shipping receptacles and particularly those designed for carrying a plurality of fragile articles such, for instance, as eggs.

10 The carrier is so constructed that the eggs may be lodged in the carrier in customary numbers, usually in dozens or multiples thereof, or in any other chosen quantity.

15 Because of the fragile or easily damaged nature of eggs, the usual egg crate has proven unsatisfactory, because it does not give sufficient protection to the eggs during shipment and it is not at all unusual to find certain of the eggs cracked or otherwise damaged.

20 In accordance with the invention, there is provided an outside or projecting casing of suitable thickness to resist the effects of bumps or jars due to blows delivered to the casing, and the inside of the casing is divided into numerous compartments with elastic or yieldable walls, each defining a compartment of a size to contain a single egg with those walls directly engaging the eggs made elastic so that direct shocks or jars are not imparted to the eggs, but those walls which directly engage the eggs are made multi-elastic.

25 Moreover provision is made for supporting the containers with surrounding cordage sustaining the exterior walls and the parts enclosed thereby, so that transportation of the container is greatly facilitated.

30 A similar provision, although on a smaller scale, is provided for the containers designed to enclose a smaller number of eggs.

35 The main features of the invention comprise means whereby the contents of the containers are protected from any direct shocks or jars and consequently damage with the parts directly engaging the eggs of cushion-

ing nature, protecting the contained eggs from the effects of shocks or jars from any direction from which such shocks may reach the eggs.

The invention will be best understood from a consideration of the following detailed description taken in connection with the accompanying drawings forming part of this specification, with the understanding that it is not confined to any strict conformity to the showing of the drawings but may be changed and modified so long as such changes and modifications mark no material departure from the salient features of the invention as expressed in the appended claims.

Referring to the drawings:—

Fig. 1 is a perspective view of a relatively large container for eggs,

Fig. 2 is a plan view of the structure of Fig. 1 showing some parts in cross section and other parts in elevation,

Fig. 3 is a vertical section through one of the members shown in Fig. 1,

Fig. 4 is a detailed section on a larger scale than the other views and confined in the main to a single egg compartment,

Fig. 5 is a view through one portion of the compartment shown in Fig. 4,

Fig. 6 is a perspective view of a unit case for receiving a minimum number of eggs and also embodying the invention,

Fig. 7 is a detailed view illustrating the wall structure where particularly heavy shocks are received,

Fig. 8 is a detailed section on a larger scale than Fig. 3 but of a similar form of the egg carrier,

Fig. 9 is a plan view of a diagonal partition member for reducing the shocks and jars to which the eggs are subjected.

Referring to the drawings, there is shown in Fig. 1 an exterior view of an egg case designed to carry a relatively large number of eggs.

The egg case in Figs. 1 and 2 is shown with extra heavy outside walls 2. The walls 2 are made up of numerous alternate layers 3, 4, see Fig. 7, of smooth and corrugated cardboard, whereby the smooth cardboard

100

constitutes supporting walls and the corrugated cardboard constitutes cushion material, whereby the exterior walls of the egg case are particularly resistant to all shocks and jars which may be transmitted toward the eggs themselves.

In the particular showing of Fig. 2 the walls 2 extend wholly about the casing and extend also across the casing midway of the 10 width thereof as well as at the end.

Furthermore the casing 1 is provided with an exterior wall consisting of a single layer 3 of cardboard or other appropriate material wholly enclosing the cushion walls 2.

15 Within the walls 2 are several superposed compartments 4 and 5, each capable of containing a relatively large number of eggs, say fifteen or more eggs for each compartment, but the particular number of eggs to 20 the compartment is immaterial.

Each compartment 4 and 5 is provided with numerous cross partitions 6 of cushion nature and each composed of a corrugated sheet 7 of cardboard and a flanking sheet 8 25 of smooth or plain cardboard, and horizontal partitions 9 are also provided.

The partitions 9 are designed to directly support the eggs on end, and for this reason the partitions are formed of cardboard 30 sheets 10, with intervening sheets 11 to provide cushioning supports for the eggs which are stood upon end in sub-compartments 11 in each larger compartment 5.

The upright walls of the unit compartment within the larger compartment 4 and 5 35 have relatively large passages 12 there-through extending through layers 13 of cardboard free from passages and serving to receive and center the side walls of eggs 40 lodged in said smaller compartments.

The top and bottom walls of each cross partition are provided with through slits 14 arranged in right angular crossing relation, thereby forming elastic supports for the 45 eggs at the ends thereof.

At the opposite ends of the respective horizontal division walls within the casing 1 are finger holes 15 enabling the operator of the egg crate to readily grasp the horizontal 50 partitions to lift them from the crate.

Moreover each compartment 4 and 5 is subdivided by diagonal partitions 6^a, of which one is shown in Fig. 9, and made of either plain or corrugated cardboard, so arranged 55 that each egg is surrounded on four sides by the partitions 6^a and on top and bottom by cushion partitions 9 with elastic slit zones 14, which effectively absorb all shocks or forces liable to damage the eggs.

60 Formed in the outer end walls of the crate 1 are upright indentations or grooves 16 carried downwardly in spaced relation with each other from the top of the case or crate 1, and thence across the bottom thereof and 65 up the other side, these grooves being ar-

ranged in pairs and terminating at the top or upper edge of the crate or case 1 in order to receive cables 17, by means of which the crate may be reinforced and the cables may be provided with handles 18, facilitating the 70 handling of the crate as a whole.

The handles 18 may be of the customary nature for carrying relatively heavy loads, and cleats 19 are made fast to the outer walls 75 of the crate to over-ride the cables 17 to hold them in place.

On the inner walls of the opposite inner faces of the crate are other cleats 20 having bulged portions 21 to fit correspondingly bulged portions 22 of the walls 2, and rivets 80 or other like fastening devices 23 secure the inner and outer cleats together with the walls 2 between them.

The cables 17 extend beneath the bottom of the crate in appropriate grooves joining 85 the upright side grooves of the crate, as shown in Fig. 3.

For holding relatively small quantities of eggs a smaller crate such as illustrated in Fig. 6 may be employed, this crate being of 90 a thickness to accommodate one single layer of eggs, which in number may be one dozen or more.

Each type of crate may be provided with a folding top, as shown at 24 in Figs. 1 95 and 6.

The cushion supports for the eggs support the top and bottom ends thereof as shown in Figs. 4 and 5, where the eggs rest upon cardboard sheets with cross-slits 14, beneath 100 which the corrugated sheets 7 have circular cut-outs 7^a permitting the sheets 8 to sink thereinto and thereby provide a cushion effect neutralizing shocks or jars to which the eggs may be subjected. This effect is due 105 particularly to the combined effect of the yielding cross-slits 14 associated with the circular openings 7^a, providing a super-sensitive support or cushion for the ends of the eggs and preventing any injury to said 110 eggs.

What is claimed, is:—

1. In a shipping receptacle or crate for eggs or the like, upright and cross partitions of composite conformation with alternate plain and corrugated layers of cardboard, an exterior protecting wall of cardboard composed of a plurality of alternate layers of plain and corrugated cardboard united to provide a wall of greater cushioning effect than the first named walls, and the exterior plural protecting cushioning layers having cord receiving grooves and retaining means exterior to and fastened thereinto.

2. In a shipping receptacle or crate for eggs or the like, upright and cross partitions of composite conformation with alternate plain and corrugated layers of cardboard, the upright layers having cut-outs to 125 lodge the side walls of the eggs and yield- 130

able seats for the ends of the eggs, an exterior protecting wall of cardboard composed of a plurality of alternate layers of plain and corrugated cardboard united to provide
5 a wall of greater cushioning effect than the first named walls, said crate or receptacle having a surrounding supporting cord or

rope and a hand-hold for carrying purposes with the ropes seated in grooves in the outer walls and provided with retaining means 10 for holding the cord in the grooves.

In testimony whereof, I affix my signature hereto.

ARTHUR T. VINSON.
